UNITED STATES PATENT OFFICE

JOSEPH FOLK, OF LA PORTE, INDIANA, ASSIGNOR TO U. S. SLICING MACHINE COMPANY, OF LA PORTE, INDIANA, A CORPORATION OF INDIANA.

MULTIPLE SPEED MECHANISM FOR SLICING MACHINES

Application filed January 8, 1926. Serial No. 79,924.

This invention relates to mechanism for driving machines for slicing meat or similar material, and has for its object the provision of a power drive for such machines which shall be of improved construction and operation, which will permit operation of the slicing machines at a plurality of different speeds, and in which interlocking mechanism is provided to prevent improper shifting of the parts of the multiple speed drive.

The invention is exemplified in the combination and arrangement of parts shown in the accompanying drawings and described in the following specification, and it is more particularly pointed out in the appended claims.

In the drawings—

Fig. 1 is a fragmentary front elevation, with parts in section, showing a slicing machine having one embodiment of the present invention applied thereto;

Fig. 2 is a section substantially on line 2—2 of Fig. 1;

Fig. 3 is a section substantially on line 25 3—3 of Fig. 2;

Fig. 4 is a section substantially on line 4—4 of Fig. 2;

Fig. 5 is an elevation with parts in section showing a modified form of the invention;

Fig. 6 is a section substantially on line 30 6—6 of Fig. 5;

Fig. 7 is a section substantially on line 7—7 of Fig. 6; and

Fig. 8 is an elevation showing the clutch 35 lever.

The invention is especially adapted for use in connection with slicing machines having rotary slicing knives and reciprocating tables. In motor driven mechanism of this nature it is desirable to be able to drive the machine at different speeds because of the varying nature of the materials to be sliced and because of the different conditions and requirements under which the slicing machine is operated. Electrical voltages vary through considerable range in different localities even though the various systems may have the same nominal rate. If the speed ratio between the motor and slicing machine 40 can be changed the desired speed can be ob-

tained even though the speed of the motor may vary considerably due to differences in voltages of the source of supply.

In the embodiment of the invention shown in the drawings, the numeral 10 designates the frame of a slicing machine having a reciprocating feed table 11 mounted to slide on guides 12. The table 11 is reciprocated by means of a connecting rod 13 operated by a crank 14 carried by an upright shaft 15 in a manner well-known to the art. The shaft 15 is journaled in a bearing 16 mounted on the frame 10 and a beveled gear 17 is carried at the lower end of the shaft 15. The gear 17 meshes with a pinion 18 carried on a shaft 19 journaled in bearings 20 in the frame 10. The end of the shaft 19 projects from the frame 10 and carries a gear 21 secured to the outer end thereof. A housing 22 encloses the gear 21 and is secured to the frame 70 10 by screws 23 extending through elongated openings 24 in the housing 22 to permit adjustment of the housing upon the frame 10.

Mounted on the housing 22 is a closed gear 75 casing consisting of separately formed sections 25 and 26. The section 25 is secured to the housing 22 by screws 27 and the section 26 is secured to the section 25 by screws 28. A disc knife 29 is secured to a shaft 30 which is journaled in ball bearings 31 carried on the rear of the casing section 25. A pinion 32 is secured to the shaft 30 between the knife 29 and the bearing 31. An idler 33 connects the pinion 32 with the gear 21. The idler 33 is 80 journaled on a stud shaft 34 which is carried by a plate 35 secured to the rear wall of the casing section 25 by screws 36. The screws 36 extend through slots 37 in the plate 35 to permit lateral adjustment of the plate.

It will be noted from Fig. 3 that the stud shaft 34 is at one side of the center line of the shafts 19 and 30. This makes it possible to move the shaft 34 by loosening the screws 36, thus shifting the gears 33 to take up any lost motion in the gear train connecting the shafts 19 and 30.

The shaft 30 is provided with a clutch member 38 journaled to rotate thereon but held against longitudinal movement by a col-

55

60

95

100

lar 39 and a shoulder 40. A pinion 41 is secured to the clutch 38. A co-operating clutch member 42 is slidably mounted on the shaft 30 adjacent the clutch member 38 and is 5 yieldingly pressed into engagement with the clutch member 38 by means of a spring 43. A pin 44 extends through the clutch member 42 and through a slot 45 in the shaft 30 holding the clutch member against rotation on the 10 shaft, but permitting it to slide longitudinally. A plunger 46 extends through a central bore in the shaft 30 and engages the pin 44. The outer end of the plunger 46 is fixed to a cap 47 by means of a threaded portion 48 and 15 a lock nut 49. The cap 47 is provided with screws 50, Fig. 1, the inner ends of which engage cam grooves or threads 52 on a stud 53 secured to the casing member 26 by screws 54. A handle 55 is connected to the cap 47 to 20 enable the cap to be rotated on the stud 53. It will be apparent that rotation of the cap by the handle 55 will force the plunger 46 inwardly and release the clutch 42 by movement thereof against the force of the spring 25 43. Movement of the handle in the opposite direction will release the plunger 46 and permit the spring 43 to re-engage the clutch members 38 and 42. The gear 41 secured to 30 the clutch member 38 meshes with a gear 56 fixed to a shaft 57 journaled in bearings 58 and 59 in the casing members 25 and 26. The shaft 57 carries two additional gears 60 and 61 which are also fixed to the shaft. The gears 56, 60 and 61 differ from one another in diameter to provide different speed ratios for 35 operating the shaft 30.

Pinions 62, 63 and 64 are mounted to slide on a shaft 65 in the casing members 25 and 26. The pinions 62, 63 and 64 are arranged to 40 mesh with the gears 56, 60, and 61, respectively, the shiftable gears being all secured to a sleeve 68 which is slidably mounted on the shaft 65, but held against rotation thereon. The sleeve 68 is engaged by a fork 69, see also 45 Fig. 4, which fork is secured to a rod 70 slidably mounted in the gear casing. The rod 70 is provided with a handle 71 by which the rod may be slid endways to shift the fork 69 and the gears 62, 63 and 64. A spring-pressed 50 detent 72 engages notches 73 in the rod 70 to retain the rod in its various positions of adjustment in which the shift gears engage with their respective co-operating gears on the shaft 57. The shaft 65 carries a worm gear 74 55 which meshes with a worm 75 on a shaft 76 journaled in the casing member 26 and extending transverse to the direction of the shaft 65.

The shaft 76 is connected to a motor shaft 60 77 operated by a motor 78 mounted on a bracket 79 adjustably connected by screws 80 to a flange plate 81 extending downwardly from the casing section 26. The bearings for the shafts journaled in the casing section 26 are provided with suitable packing to

form a closed casing for the gears housed therein so that the gear casing may be filled with suitable lubricating material.

The detent 72 is provided with an extension pin 82 which bears against the cap 47, thus normally holding the plunger in engagement with a notch 73 and preventing the rod 70 from being shifted longitudinally. When the handle 55 is shifted to release the clutch 42 an opening 83 in the housing 47 will be 75 brought into registration with the end of the detent 72 so that when the handle is in position to fully release the clutch 42 the rod 70 may be moved to shift the gears, but in all other positions of the handle 55 the rod will 80 be held against movement. This makes it impossible to shift the gears while the shaft 30 is rotating to drive the slicing machine. While the rod 70 is in any intermediate position the pin 82 will be held in the opening 83 and the clutch handle 55 will be locked against rotation. This makes it impossible to re-engage the clutch until the gears are properly meshed.

The cap 47 is provided with stops 84 which engage a pin 85 in the support for the stud 53 to limit the movement of the handle. The release of the clutch disconnects the load from the motor at the time that the gears are shifted but at the same time permits the gears to continue to rotate so that they may be easily meshed when shifted from one speed to another. The interlocking mechanism makes it impossible to shift the gears into mesh while the load is on the driving mechanism. The mechanism also makes it impossible to throw the clutch into engagement while the gears are in an intermediate position. Engagement of the clutch can only be effected after the gears have been brought properly into mesh at one or the other of the speed ratios. The adjustable bracket for the motor makes it possible to accommodate the motor support to motors of various styles and sizes. The gearing provides a reduction train from the motor to the drive and a further reduction train from the drive to the reciprocating table. This arrangement has considerable advantage over a drive connected with the operating mechanism for the reciprocating table for in that case the speed must be reduced from the motor to the table operating mechanism and again stepped up to drive the knife. It will be seen that the entire change speed mechanism and motor are mounted on a self-contained housing so that the motor drive and multiple speed gearing may be easily applied to a slicing machine previously provided with a hand or other form of drive.

In order to prevent danger of overbalancing the machine a separate supporting foot 86 may be connected to the housing 22 by means of a suitable bracket 87. An adjustable screw 88 is preferably provided for regulating the position of the foot 86. 130

In the form of the invention shown in Figs. 5, 6, 7 and 8, the shaft 30 and its connected parts are similar to those already described but the counter shaft 57 having the change speed gears 56, 60 and 61 is journaled at a higher position on the horizontal level with the shaft 30. The shaft 65 which carries the sliding gears 62, 63 and 64 is journaled below the shaft 57 and occupies the same relation to the shaft 57 as it does in the form already described. This shaft will be considerably nearer the shaft 30, however, and the three shafts will be arranged in a triangular position relative to each other as shown in Fig. 7 so that a more compact arrangement is secured. This will leave space for a motor housing 90 beneath the portion 26 of the gear housing. The motor 28 is disposed within the housing 90 and is secured to an inner side wall 91 thereof. The motor shaft 92 is connected by pinions 93 and 94 and an idler 95 with a worm shaft 96 journaled in the gear housing 26. The shaft 96 is provided with a worm 97 which meshes with a gear 98 on the shaft 65. The motor housing 90 is provided with a sleeve 99 which receives a bearing 100 for the shaft 96. The bearing 100 is fixed in a sleeve 101 forming a part of the gear housing 26. The disposition of the motor beneath the gear housing 26 effects an economy of space at the rear of the slicing machine, that is, at the left of the knife, as viewed in Fig. 7. This space economy is of especial importance where the slicing machine is placed on a counter having a glass front. In such an arrangement, the rear of the machine or the side at the left of the knife, as viewed in Fig. 7, is arranged adjacent the glass front and if the motor projects beyond the rest of the machine, it is impossible to place the machine as close to the glass as could otherwise be done. The arrangement shown in Fig. 7 makes it possible to bring the rear extremity of the motor casing in substantial alinement with the rear of the slicing machine frame so that the motor does not occupy a position that would interfere with the proper placing of the machine on a counter having a glass front. The position of the motor also makes it possible to enclose it in a housing which harmonizes closely with the remainder of the machine.

In the form of the invention shown in Figs. 5, 6, 7 and 8, a somewhat different operating mechanism for the gear shaft and clutch from that previously described is provided. A slide rod 102 is mounted in the gear housing and is provided with a yoke 103 which engages the carrier for the shift gears 62, 63 and 64 in a manner similar to the yoke 69 previously described. The outer end of the shift rod 102 is provided with rack teeth which engage a pinion 104 secured to a shaft 105 journaled in a bearing 106 formed integral with a tubular extension 107 projecting

outwardly from the gear housing 26. The shaft 105 is provided with a hand wheel 108 and a cam disc 109. The disc 109 engages a spring detent 110 which holds the disc from accidental rotation when the shift gears are moved into their running positions. When the hand wheel 108 is rotated to shift the gears, the detent 110 is pushed backwardly by inclined faces on the disc 109. An indicator 111 co-operates with a dial surface 112 connected with the hand wheel 108 to indicate the position of the shift gears.

The plunger 46 for operating the clutch 42 is arranged to register with the upper end of a lever 113 journaled at 114 on a bracket 115 projecting outwardly from the gear housing 26. The lever 113 is provided with a stop 116 which registers with a pin 117 on the detent 110 when the clutch 42 is in engagement with the clutch member 38. This will prevent rotation of the hand wheel 108 to shift the gears while the clutch is engaged. The upper end of the lever 113 may be provided with a contact screw 118 held in place by lock nuts 119. The lower end of the lever 113 registers with a cam 120 secured to the end of a shaft 121. The shaft 121 is provided with a stop pin 122 arranged to engage a stop surface 123 causing the cam 120 to hold the lever 113 in position to retain the clutch 42 out of engagement. The shaft 121 is operated by a hand wheel 124 positioned adjacent the front or operator's end of the slicing machine. When the hand wheel 124 is rotated to move the lever 113 and disengage the clutch 42, the stop 116 will be moved out of registration with the pin 117 so that the hand wheel 118 may be rotated to shift the gears. If the hand wheel is stopped with the gears in an intermediate or neutral position, the pin 117 will project into the path of the stop 116 and prevent reengagement of the clutch until the gears are in proper mesh for driving the knife at one of the three speeds. The connection from the knife spindle to the driving mechanism for the reciprocating table is the same in this species of the invention as in the one previously described.

I claim:

1. The combination with a slicing machine frame, of a gear casing secured to said frame, a knife mounted on said gear casing, gears arranged within said casing for driving said knife, and a support for said casing spaced outwardly from said frame.

2. The combination with a slicing machine frame, of a feed table mounted for reciprocation on said frame, a gear casing detachably connected with said frame, a knife spindle journaled in said gear casing, a disc knife carried by said spindle, a clutch mounted on said spindle, a shiftable gear train having driving connection with one element of said clutch, said gear train including a set of change speed shift gears, a motor for driving

- said gear train adjustably carried by said gear casing, a slide bar for moving said shift gears, a spring detent for holding said slide bar in its various positions of adjustment in which said gear train is in driving connection, and a movable member for operating said clutch, said movable member having means for engaging said detent to control the relative time of operation of said clutch and shift gears.
- 10 3. In a slicing machine, the combination with a horizontally disposed knife spindle of a housing enclosing said spindle, driving gearing disposed within said housing and at one side of said knife spindle and operatively connected therewith, a motor arranged beneath said housing and partially covered thereby, and driving connection between said motor and gearing.
- 15 4. In a slicing machine, the combination with a knife spindle, of change speed gearing disposed at one side of the vertical plane of the axis of said spindle, a worm shaft extending transversely to the axis of said spindle for driving said change speed gearing, a motor disposed beneath said worm shaft and having its axis of rotation parallel to the axis of said worm shaft, and driving connection between said motor and worm shaft.
- 20 5. In a slicing machine, a supporting frame, a rotary slicing knife, a spindle for supporting said slicing knife, a motor for driving said spindle, a clutch mounted on said spindle for connecting said slicing knife with said motor, a lever for operating said clutch, an operating rod for said lever, and means for actuating said rod, said actuating means being disposed adjacent the front of said supporting frame.
- 25 6. The combination with a slicing knife, of a support for said knife, a spindle journaled in said support and having said knife mounted thereon, change speed gearing for said spindle disposed at one side of the vertical plane of the axis thereof, a housing for said gearing, a motor for driving said change speed gearing, and a housing for said motor disposed beneath the housing for said gearing.
- 30 7. In combination, a horizontally disposed driven shaft, a horizontally disposed transmission shaft extending transversely of said driven shaft, reduction gearing for transmitting movement from said transmission shaft to said driven shaft, a motor support, a motor mounted therein having its shaft disposed substantially parallel with said transmission shaft, and means for transmitting motion from said motor shaft to said transmission shaft.
- 35 8. In combination, a horizontally disposed driven shaft, a horizontally disposed transmission shaft arranged below and transversely to said driven shaft, a motor disposed below said transmission shaft, means for transmitting motion from said transmission shaft, a bearing for said transmission shaft, and a support for said motor mounted on said bearing.
- 40 9. In combination, a driven shaft, two intermediate shafts having their axes parallel with said driven shaft and disposed in triangular relation, change speed gearing connecting said intermediate shafts, a clutch interposed between said change speed gearing and said driven shaft, a worm shaft extending transversely of said intermediate shafts and having driving connection with one of said intermediate shafts, and means for driving said worm shaft.
- 45 10. In combination, a driven shaft, a gear mounted on said driven shaft, a clutch for connecting said gear to said driven shaft, a pair of intermediate shafts, a gear mounted on one of said intermediate shafts and engaging the gear on said driven shaft, worm gearing for driving the other of said intermediate shafts, and change speed gearing between said intermediate shafts.
- 50 11. In combination, a driven shaft, a pair of intermediate shafts, clutching mechanism driven by one of said intermediate shafts for driving said driven shaft, a worm gear for driving the other of said intermediate shafts, change speed gearing interposed between said intermediate shafts, means for shifting said change speed gearing, means for operating said clutch, and interlocking mechanism between said change speed gearing and clutch operating mechanism for preventing shifting of said change speed gearing while said clutch is in engagement and for preventing engagement of said clutch when said change speed gearing is out of operative relation.
- 55 12. In combination with a slicing machine having a rotary slicing knife, of a horizontally disposed driven shaft, a driving connection between said shaft and knife, a transmission shaft arranged below and transversely to said driven shaft, a motor disposed below said transmission shaft, means for transmitting motion from said motor to said transmission shaft, a bearing for said transmission shaft, and a support for said motor mounted on said bearing.
- 60 13. In a slicing machine, a knife spindle, a housing in which said spindle is journaled, a worm shaft for driving said spindle, clutch mechanism interposed between said worm shaft and spindle, a motor supported beneath said housing and having its shaft arranged parallel with said worm shaft, means for driving said worm shaft from said motor, and a support on which said spindle, spindle housing, worm shaft and motor are removably mounted.
- 65 14. The combination with a slicing machine having a reciprocating table and a rotary knife spindle, of a knife supported by

said spindle, a driving connection between said table and spindle, a bearing support, a bearing for said spindle removably carried by said support, a housing connected with said bearing, clutch mechanism within said 5 housing, a motor supported by said housing, and gearing driven by said motor for driving said spindle through said clutch mechanism.

15. The combination with a slicing machine having a reciprocating table, a rotary knife spindle, driving connection between said spindle and table, and a bearing support for said spindle, of a gear housing having bearings for said spindle and a projection surrounding said spindle and carried by said bearing support, a clutch mounted on said spindle in said gear housing, worm gearing for driving one member of said clutch, a handle mounted on the outside of said housing 20 for operating said clutch, a motor for driving said gearing, and a support for said motor adjustably mounted on said housing.

16. In a slicing machine, a knife spindle bracket, a gear housing, a motor support mounted on said gear housing, a knife spindle journaled in said gear housing, gearing in said gear housing connected with said knife spindle for driving the same, and means on said gear housing engaging said knife spindle bracket for supporting said housing and motor support on said bracket, the axis of rotation of said motor being at substantially right angles to said spindle.

In testimony whereof I have signed my 35 name to this specification on this 5th day of January, A. D. 1926.

JOSEPH FOLK.
